LACE YOKE AND METHOD OF MAKING THE
SAME

Solomon Goodman, Brooklyn, N. Y.

Application November 23, 1934, Serial No. 754,517

2 Claims. (Cl. 28—1)

This invention relates to a lace yoke, or "galoon" and method of making the same.

It is the present style to provide a lace yoke or galoon insert in the front top of ladies' garments such as underslips, nightgowns, and the like, which is commonly formed by stitching two or more pieces of lace together to produce a decorative design and to obtain the desired shape neck line. This piecing together of the lace is made necessary for the reason that the lace is usually woven in strip form and the designs are of arbitrary shapes and sizes, and to cut the same to a particular neck line shape for use as a lace yoke would necessitate the cutting into the design figures and the repeat units thereof, and results in the destruction of the symmetry of the design for the purpose intended.

It is therefore the main purpose of this invention to provide a method whereby a yoke may be formed in a single piece from a strip of lace, the shape of the neck line being worked in the particular lace design and being of a predetermined length to adapt the yoke for use upon garments of various sizes.

A further object of the invention resides in a method of making lace yokes which facilitates the cutting out of identical designed yokes from a single length of lace without undue waste, due to the novel arrangement of the repeat design units forming the strip of lace.

Other objects of the invention will appear as the following specification is read in conjunction with the accompanying drawing, in which:

Figure 1 is a plan view of a strip of lace embodying a plurality of repeat design units from which the lace yokes are formed in accordance with my invention.

Figures 2 and 3 are views similar to Figure 1, but showing the steps in the cutting process for forming the yoke.

Figure 4 is a plan view of the finished yoke per se.

Figure 5 is an elevational view of a lady's garment with the lace yoke and trimming embodied therein.

Referring to the drawing by reference characters, the numeral 10 designates a strip of lace woven in accordance with my invention and which includes a series of repeat design units. The repeat design units 11 extend inwardly from opposite sides of the lace strip and those disposed along one side are staggered with respect to those extending inwardly from the opposite side.

Each design unit 11 includes a pronounced

line of demarcation 12 which extends inwardly from the marginal edge of the lace strip and in the present instance the shape is shown as curved. It is the shape of this line of demarcation which predetermines the style of neck line of the lace yoke to be formed. The line of demarcation 12 divides the design unit into two sections, namely, a yoke forming section 13 and a trimming section 14. The sections 13 and 14 are normally secured together by the background netting or stitching 15 which may be cut without causing unravelling of the flower design or other woven design figures which make up the lace design.

After the strip of lace 10 has been formed with a design having the above mentioned design features, the repeat units 11 may be cut inwardly from opposite sides of the strip, the neck line of the yoke section 13 being first cut on the line of demarcation 12 as shown in Figure 2 of the drawing. The yoke section 13 is next cut from the strip along the outline of the remaining portions of the design units, there being a space between the design features of the adjacent repeat units. This operation is shown completed in Figure 3 of the drawing wherein the trimming section 14 25 and yoke section 13 are shown separated from each other and from the remainder of the lace strip 10.

After completion of the cut out operation, any loose threads around the cut out pieces 13 and 14 may be trimmed off to provide a clean edge as shown in Figure 4 wherein the finished lace yoke article or galoon 16 is shown having a curved neck line 17.

By reason of actual measurements, I have discovered that a span of nine inches across the neck line 17 is adaptable for fitting the chest of the average size woman when the yoke is embodied in a lady's garment such as an underslip 18 shown in Figure 5 of the drawing. In view of the standard measurement, it is unnecessary to weave the lace design repeat units in different sizes, unless the need is one in which the garment to be trimmed is of an unusually large or small size.

In the drawing, I have shown a lace design in which the lace yoke may be cut from opposite sides of the lace strip without waste, as those extending inwardly from one side interfit with those extending inwardly from the other side, and the yoke cut along the dividing line therebetween. However, any waste from cutting may be utilized for additional trimming upon the garment, and in Figure 5, two flower designs 19 are cut from adjoining design units and are shown for the above purpose. Such use may also be made by the trim-

ming piece 14 as a whole or from portions of the design cut therefrom. In the present instance, the trimming piece 14 is shown inserted as a whole at the top of the back of the garment 18.

5 In the trade, it is the practice for the lace manufacturer to make up the same in strip form, and to sell the lace in such form to the garment manufacturers who cut the lace into pieces to form various style trimmings for ladies' under-clothing and night attire. By the use of the method herein shown and described, the garment manufacturer is able to more rapidly cut the yoke from the strip and to more readily visualize the design of yoke at the time of purchase of the lace in strip form. Although I have mentioned that the lace is purchased by the garment manufacturer in strip form and the yokes later cut therefrom, it will be understood that the lace manufacturer or lace dealer may cut the yoke and trimming from the strip and mount them upon mats to be sold to the garment manufacturers as a lace yoke set.

10 While I have shown and described what I deem to be the preferred embodiment of my invention, I wish it to be understood that such modifications may be resorted to as come within the scope of the appended claims.

15 Having thus described the invention, what I claim as new and desire to secure by Letters Patent of the United States, is:—

1. An article of manufacture comprising a strip of lace material having parallel side edges and provided with a series of repeat designs of predetermined configuration woven therein and defining garment trimming units, each of said units being severable from the strip and having a definite line of demarkation extending inwardly from one edge to define a cutting guide along which to sever a segment from the unit to produce a neck yoke, said segment and said neck yoke each 10 embodying a complete design and constituting individual garment trimming elements. 5

2. An article of manufacture comprising a strip of lace material having parallel side edges and provided with a series of repeat designs of predetermined configuration woven therein and defining garment trimming units, said units being arranged in staggered relation with the opposite marginal edges of the strip forming part of the marginal edge of adjacent units, each of said 15 units being severable from the strip along their abutting edges and having a definite line of demarkation extending inwardly from one edge to define a cutting guide along which to sever a segment from the unit to produce a neck yoke, said segment and said yoke each embodying a complete design for constituting individual trimming elements. 20 25
